E. G. HESS
RADIATOR SHIELD

Filed Feb. 21, 1927

UNITED STATES PATENT OFFICE.

EMIL GEORGE HESS, OF TORONTO, ONTARIO, CANADA.

RADIATOR SHIELD.

Application filed February 21, 1927. Serial No. 169,914.

My invention relates to improvements in radiator shields, and the object of the invention is to devise a simple and cheap shield which is easily installed without tools or 5 skilled labour, and so constructed that the radiator top may be uncovered at the will of the user without detaching the shield from its supports, and it consists essentially of the arrangement and construction of parts as 10 hereinafter more particularly explained.

Fig. 1 is a perspective view of the top portion of a radiator, the sections of which have rounded upper ends, shown adjacent a wall and my shield applied thereto.

Fig. 2 is a cross sectional view through Figure 1 showing the initial position of the shield prior to applying it to the radiator in dotted lines.

Fig. 3 is a similar view to Figure 2 on a 20 slightly smaller scale showing the cover of the shield in its raised position.

Fig. 4 is a similar view to Figure 2 showing my shield applied to a two column radiator.

Fig. 5 is a sectional detail showing an intermediate support for the cover member of the shield.

Fig. 6 is an enlarged perspective detail of one of the supporting brackets of my shield 30 cover.

Fig. 7 is a similar view to Figure 2 showing my device applied to a radiator having a square top.

In the drawing like characters of reference 35 indicate corresponding parts in each figure.

Referring to Figures 1 to 3 and 5. 1 indicates the upper portion of a radiator, the sections of which are formed with rounded upper ends 1*. 2 is a wall adjacent to which 40 the radiator 1 is situated. 3 is a cover member of my radiator shield which is adapted to set normally in a horizontal position on top of the radiator.

In order to support the cover member in 45 this position I provide the brackets, one of which is illustrated in detail in Figure 6. This bracket is formed from a single length of stiff yet bendable wire, such wire being bent to form a horizontal portion 4 which extends between the sections of the radiator and 50 rests upon the interconnection 1° between two of the sections as clearly indicated in Figure 2.

The ends of the portion 4 are looped at 5 55 and 6 to provide downwardly extending ver-

tical portions 7 and 8 which extend to the front and rear of the interconnection 1° so as to resiliently grip it. The vertical portion 8 at its lower end is provided with an outwardly extending extension portion 8° terminating in a horizontally bent portion 8*, which in the construction of radiator shown in Figures 1, 2 and 3 extends against the inner side of the column 9 of one of the sections of the radiator as clearly indicated in Figure 1, thereby holding the horizontal portion 4 in its normal position when pressure is brought to bear on the inner end of such portion.

An extensible arm formed by the loops 10, 70 11 and 12 extends inwardly from the bracket portion 7 forming a continuation of such portion, the extremity of the upwardly extending portion of the loop 12 terminating in an inturned loop 13 which terminates in a horizontal outwardly extending portion 14 which is bent back upon itself at 15 so as to provide an inwardly horizontal portion 16 terminating in a laterally outwardly extending portion 17.

18 are eyes secured in the frame of the cover member 3 as shown in Figure 2 into which the laterally extending portions 17 of the brackets extend thereby forming a pivotal connection for the cover member 3.

It will be noted that the portion 17 of the brackets at each end of the radiator extend in opposite directions and when inserted in the eyes 18 are sprung inwardly towards each other so that when inserted in the eyes they exert outward pressure in opposite directions against the eyes thereby holding them firmly in place within the eyes.

When installing my shield in position all it is necessary to do is to take a pair of 95 brackets such as illustrated in Figure 6, such brackets being formed as right and left hand brackets and inserting a bracket between two sections of the radiator so that the portions 8 pass between the vertical columns of the sections, and the portion 8° into engagement with the inner edge of the outer column. The bracket is then forced downward so that the portions 8 and 7 pass to the front and rear of the interconnection 1° until the portion 4 100 rests upon the top of such interconnection.

The portion 16 is bent up into an angular position indicated by dotted lines in Figure 2.

The cover 3 is then pivotally engaged with such arms as previously described, manual 110

pressure being then brought to bear against the inner portion of the cover so as to force the portion 16 downward towards the full line position shown in Figure 2, carrying the 5 inner edge of the cover tightly against the wall.

In order that the cover may be adapted to fit against a wall varying in distance from the radiator all it is necessary to do is to squeeze 10 the loop portions 10, 11 and 12 manually together or draw them apart as the case requires so that when the cover is forced downward to engage the wall at its inner edge the loop portions 10, 11 and 12 will be forced together to adapt the length of the extensible arm to the intervening distance between the radiator and wall and thereby resiliently hold 15 the cover 3 against such wall to form a tight fit, and thereby effectually prevent the hot air rising at the back of the radiator from passing up the wall deflecting it outward beneath the cover into the room.

In Figure 3 I have shown the cover in its raised position thereby leaving the top of the 20 radiator exposed so that the user may utilize it for various domestic purposes for which the radiator top is commonly employed.

Where long radiators are used it may be necessary to provide an intermediate support 30 for the cover, such support I have illustrated in Figure 5, which consists of a horizontal portion 19 extending transversely upon the top of the radiator interconnection and terminating in looped ends 20 and 21 upon 35 which the cover rests, such loop portions being provided with downwardly extending extensions 23 and 24 which pass to each side of the radiator interconnection so as to grip it in the position illustrated in Figure 5.

40 In round type radiators such as illustrated in Figures 1 to 3 and 5 the loops 5 and 6 of the brackets are in horizontal alignment so as to form a support for the cover to hold it in a horizontal position.

45 In Figure 7 I have shown my device applied to a radiator having a square top. In this case the loops 5 and 6 are situated below the level of the radiator top and the square top of the radiator itself forms the support 50 for the cover holding it in a horizontal position.

In Figure 4 I have shown my device applied to a radiator having two columns.

From this description it will be seen that I 55 have devised a very simple construction of

radiator shield which will be cheap to manufacture, easily installed without tools or skilled labour, and which is so constructed that the cover forming the top of the shield may be raised whenever desired from off the 60 radiator so that the radiator top may be utilized, and which is so constructed as to fit tightly against the adjacent wall situated at any distance from the adjacent radiator so as to form a deflector for hot air passing 65 upwardly from the back of the radiator to direct it outward beneath the top of the shield cover into the room.

What I claim as my invention is:

1. A radiator shield comprising a bracket 70 adapted to engage a radiator at the top adjacent a wall and formed from a single piece of bendable wire and formed at one end to engage the interconnecting portion between the radiator sections, a cover member adapted to extend over the top of the radiator, a horizontal arm forming a pivotal support at its end for the cover member, and connecting means between the arm and the engaging portion of the bracket adapted to be adjusted 75 to conform to the distance between the radiator and the wall to hold the cover member in engagement with said wall.

2. A radiator shield comprising a bracket 80 adapted to engage a radiator at the top adjacent a wall and formed from a single piece of bendable wire and formed at one end to engage the interconnecting portion between the radiator sections, a cover member adapted to extend over the top of the radiator, a horizontal arm forming part of the bracket and forming a pivotal support at its end for the cover member, and means for adjusting the cover member towards or away from the wall. 85

3. A radiator shield comprising a bracket 90 adapted to engage a radiator at the top adjacent a wall and formed from a single piece of bendable wire and formed at one end in inverted U-shaped form to engage the interconnecting portion between the radiator sections, the outer arm of the U depending downward and turned horizontally at its extremity to bear outward against the outer leg of the radiator, a cover member adapted to extend over the top of the radiator, and means for 100 pivotally mounting the cover member upon the bracket adjacent one longitudinal edge so that such edge may assume a position close to or remote from the radiator as desired. 105

EMIL GEORGE HESS.
